UNITED STATES PATENT OFFICE.

ANTHONY PETTICORE, OF SEDRO WOOLLEY, WASHINGTON.

TURBINE.

No. 910,228.

Specification of Letters Patent.

Patented Jan. 10, 1909.

Application filed June 16, 1908. Serial No. 438,747.

To all whom it may concern:

Be it known that I, ANTHONY PETTICORE, a citizen of the United States, and a resident of Sedro Woolley, in the county of Skagit 5 and State of Washington, have invented a new and Improved Turbine; of which the following is a full, clear, and exact description.

This invention relates to certain improvements in turbines adapted to be operated by a motive fluid, and relates more particularly to that type of turbine in which the motive fluid escapes through nozzles against a rotor or impact wheel.

15 The object of the invention is to provide certain improvements in the means for controlling the escape of the fluid, and also in the means whereby the fluid after impacting at high pressure with one rotor may flow 20 through a second nozzle in a partition plate to impact with a second or low pressure rotor.

Reference is to be had to the accompanying drawings, forming a part of this specification, in which similar characters of reference indicate corresponding parts in all the 25 figures, and in which—

Figure 1 is a transverse section through a 30 turbine constructed in accordance with my invention, said section being taken on the line 1—1 of Fig. 2; Fig. 2 is a central longitudinal section taken on the line 2—2 of Fig. 1; Fig. 3 is a transverse section taken on the line 3—3 of Fig. 2; Fig. 4 is a longitudinal 35 section on the line 4—4 of Fig. 1; Fig. 5 is a central longitudinal section on the line 5—5 of Fig. 3; and Fig. 6 is a sectional detail on the line 6—6 of Fig. 3.

In the specific form of turbine illustrated 40 in the accompanying drawings and embodying my invention, there is provided a casing 10, which may have a removable end plate 11, which together with the body of the casing, serve to support a main drive shaft 12. 45 Within the casing, there is provided a partition 13 which subdivides the interior of the casing into two separate compartments; one, a high pressure compartment 14 and the other a low pressure compartment 15. Rigidly 50 mounted on the shaft 12, there are provided three rotors or impact wheels, two of them, 16 and 17 being mounted in the high pressure compartment 14, and the other, 18, being mounted in the low pressure compartment. 55 Each wheel is provided with a plu-

rality of pockets or buckets in one face thereof, adjacent the periphery. The pockets 19 and 20 of the rotors 16 and 17 are on the faces which are toward each other, while the pockets 21 of the rotor 18 are on the face 60 toward the partition 13 and are slightly larger than the pockets 19 and 20. The walls of each pocket are at an angle to the face of the rotor and also at an angle to the direction of rotation thereof, as will be set 65 forth more fully hereinafter. The pockets 19 and 20 are so disposed in respect to each other that they do not receive the steam or other motive fluid at the same time.

Intermediate the two pressure impact 70 wheels or rotors 16 and 17, I provide a controlling member 22, serving as a combined steam chest, throttle, a shut-off valve, nozzle, steam inlet, speed regulator, and automatic feeder, to both of the high pressure rotors. 75 This member 22 is preferably in the form of a longitudinally-movable bar extending through the casing substantially tangentially and in a plane at right angles to the main drive shaft. The ends of the bar extend 80 through the walls of the casing and the center portion of the bar is disposed intermediate the two rotors 16 and 17 and closely adjacent to each. The interior of the bar is provided with two chambers 23 and 24, and 85 in the upper surface of the bar are inlet ports 25 and 26 through which steam or other motive fluid may be admitted to the two chambers. In the upper wall of the casing 90 above the bar, are two steam delivery conduits 27 and 28, leading from a common source and so disposed that only one of them can communicate with its corresponding port in the bar at one time. With the bar in the position shown in Fig. 1, the steam may be 95 admitted through the conduit 27 and port 25 to the chamber 23, while if the bar be moved inwardly to its limiting position, the steam may be admitted through the conduit 28 and port 26 to the chamber 24. The 100 chamber 23 terminates in two discharge nozzles 29, extending through the outer walls of the bar toward the two rotors and closely adjacent the rows of pockets therein. These nozzles extend at an angle of substantially 105 forty-five degrees to the further side of the corresponding pocket into which the steam flows from the nozzles. The chamber 24 is provided with two similar nozzles 30, through 110 which the steam may be admitted to the

- pockets, and the nozzles 30 are so directed that when steam is admitted it will strike the pockets on the opposite sides thereof from what the steam does which enters through 5 the nozzles 29, as will be noted from an inspection of Fig. 4. With the bar as shown in Figs. 1 and 2, the steam entering the chamber 23 issues through the nozzle 29 and causes the two rotors to move simultaneously 10 in the direction indicated by the arrow in Fig. 1. If the bar be moved inwardly to its limiting position, the steam will issue through the nozzles 30 and the two rotors will move in the reverse direction.
- 15 The ports 25 and 26 are so arranged in respect to the inlet conduits 27 and 28, that when the bar is in the intermediate position, steam cannot enter either of the chambers 23 and 24, and the bar thus serves as a shut-off 20 valve. By varying the position of the bar, the amount of steam admitted to either chamber may be controlled to vary the speed 25 of the engine. The pressure of the impact of the steam against the walls of the pockets is substantially the same on both rotors, and the steam after escaping from the pockets 30 may circulate upon all sides of both rotors, so that the pressure at all points within the chamber 14 will be equal. All end thrust on the high pressure rotors or the shaft 12 is completely eliminated.
- The partition plate 13 forms one end wall 35 of the high pressure chamber or compartment 14, and in this partition are passages through which the steam may escape from the high pressure compartment 14 into the low pressure compartment 15 and into the pockets of the low pressure rotor 18. As many of these passages may be provided as 40 desired, but, as illustrated, there are provided two pairs of passages, one pair 31 and 32 being disposed diametrically opposite to the other pair. The passages of each pair extend at an angle to each other, as indicated 45 in Fig. 6, and serve as nozzles through which the steam is delivered against the pockets of the low pressure rotor. The portion of the partition adjacent the nozzles is slightly raised to bring it into close proximity with 50 the surface of the rotor, or rather the remaining portion of the surface of the partition is cut away to bring it away from the rotor and permit the escape of steam from the pockets 21.
- 55 Within the high pressure compartment and adjacent the inner surface of the partition 13, is a member 33 for controlling the flow of steam through the nozzles 31 and 32. As shown, this controlling member comprises a collar rotatably mounted on a shoulder 34 of the partition and having arms 35 serving as valve plates and disposed adjacent the nozzles. With the controlling member 33 in the position indicated in Fig. 3, the steam may flow through the nozzles 32 to 65 rotate the low pressure rotor in one direction, while by slightly rotating the controlling member the nozzles 32 may be closed and the nozzles 31 uncovered, so that the low pressure rotor will travel in the reverse direction. 70
- For operating the controlling member 22 and the controlling member 33 simultaneously, I preferably provide an operating lever 36 pivoted to the wall of the casing and 75 having a link 37 connecting it to the end of the controlling member 22. A second link 38 connects the lever to a rod 39 extending through a stuffing box in the wall of the casing, and the inner end of the rod 39 is 80 connected by suitable links 40 and 41 and a lever 42 to an arm 43 on the controlling member 33. Adjacent the operating lever 36 is a quadrant 44 for engagement with a dog 45 carried by the lever and serving to 85 hold the latter in the predetermined position.
- By means of the connections above described, a movement of the lever 36 operates the controlling members 22 and 33 simultaneously, so as to direct the steam to both the high pressure and the low pressure rotors at the same time and to rotate them in the same direction. The steam after operating on the low pressure rotor may escape 90 from the low pressure chamber 15 in any suitable manner, as, for instance, through a conduit 46, as shown in Fig. 2.
- Having thus described my invention, I claim as new and desire to secure by Letters 100 Patent:
1. In combination, a rotor having a series of buckets, a member arranged substantially tangentially of said rotor and serving to deliver a motive fluid against the rotor, and means whereby the longitudinal movement of said member shuts off the supply of motive fluid. 105
2. In combination, a rotor having a series of buckets, a member arranged substantially tangentially of said rotor and serving to deliver the motive fluid to said rotor to rotate the latter in one direction, and means whereby the longitudinal movement of said member directs the motive fluid against the rotor 110 to rotate it in the opposite direction. 115
3. In combination, a casing, a rotor within said casing and having buckets adjacent the periphery thereof, a member extending through said casing adjacent said series of buckets and serving to deliver motive fluid to said buckets, and means whereby the longitudinal movement of said member shuts off the supply of motive fluid. 120
4. In combination, a casing, a rotor within said casing and having buckets adjacent the periphery thereof, a member extending through said casing adjacent said series of 125 buckets and serving to deliver motive fluid to said buckets, and means whereby the longitudinal movement of said member shuts off the supply of motive fluid.

buckets and serving to deliver motive fluid to said buckets to rotate said rotor in one direction, and means whereby the movement of said member directs the motive fluid 5 against the buckets to rotate the rotor in the reverse direction.

5. In combination, a casing, a rotor mounted therein and having a series of buckets on one side thereof adjacent the 10 periphery, a controlling member extending through said casing adjacent said buckets and having two separate motive fluid chambers, each having an inlet port and a discharge nozzle extending at an angle to the 15 general direction of the length of said member, and said nozzles extending in substantially opposite directions, and means whereby the movement of said member shuts off the supply of motive fluid to one of said 20 chambers and admits motive fluid to the

other of said members to reverse the direction of rotation of the rotor.

6. In combination, a casing, a drive shaft extending therethrough, two rotors mounted on said drive shaft and each having a series 25 of buckets on the side thereof adjacent the other rotor, and a motive fluid controlling member having an inlet port and oppositely-disposed discharge nozzles and extending between said rotors adjacent their periphery 30 and movable to control the flow of fluid through said nozzles.

In testimony whereof I have signed my name to this specification in the presence of two subscribing witnesses,

ANTHONY PETTICORE.
